ELEVATOR GUIDE RAIL FASTENING
DEVICESelden Bradley Sanford, Yonkers, N. Y., assignor
to Otis Elevator Company, New York, N. Y., a
corporation of New Jersey

Application January 14, 1942, Serial No. 426,763

1 Claim. (Cl. 189—35)

The invention relates to elevator guide rail installations.

Guide rails are provided in elevator installations for both the car and the counterweight. Those for the car are usually arranged oppositely, one on each side of the hatchway with those for the counterweight arranged oppositely along one of the hatchway walls. It is important that the rails be set vertical, i. e., with all points along the face of the rail in the same vertical plane and also all points along each side of the rail in the same vertical plane, with opposing rails uniformly spaced and with the corresponding sides of opposing rails in the same plane. The vertical setting of a rail is done by measurement in connection with a plumb line and the rail is usually secured in place by means of clips bolted to rail brackets. Shims are utilized in positioning the faces of the rails. The vertical alignment of the sides of the rails, however, is obtained by pushing the rails sidewise into aligned position and the clips are relied on to hold the rails in place. The spacing and lining up of opposite rails is obtained by the use of gauges. While the faces of the rails may be readily positioned by means of different size brackets and shims, it is often a difficult matter to set the sides of the rails, because of variation due to the construction of the building, especially where the rail brackets can not be shifted sidewise.

The object of the invention is to provide fasteners for elevator guide rails which facilitate aligning the sides of the rails and insure the retention of the sides of the rails in alignment.

Features and advantages of the invention will be apparent from the following description and appended claim.

In the drawing:

Figure 1 is a side view of several sections of an elevator car guide rail mounted in the hatchway in accordance with the invention;

Figure 2 is an enlarged detail of a portion of the guide rail at a mounting bracket, illustrating the rail in adjusted position under one installation condition;

Figure 3 is a similar view, illustrating the rail in adjusted position under another installation condition;

Figure 4 is a section taken along the line 4—4 of Figure 2; and

Figure 5 is a front view of a rail bracket.

The invention will be described by way of illustration in connection with one of the guide rails for an elevator car. In elevator installations, the rails 7 come in sections which are se-

cured together by means of fish plates 9, bolted to the rails as shown in Figure 1. The rails are mounted vertically on rail brackets 10. The rail brackets are secured along the hatchway wall 11 at spaced intervals, the number of brackets and their spacing depending upon the requirements of the particular installation. Various types of brackets may be employed, depending upon the character of the building construction. A chair type bracket has been illustrated. These brackets may be fastened in various ways, depending upon the manner and type of building construction, but are illustrated as secured by bolts 12 extending into expansion shells 16 in the hatchway wall. The holes 13 for the shells are made with star drills and these holes are roughly aligned vertically when made. The feet 14 of the brackets are provided with apertures 15 through which the bolts extend.

20 The faces of the brackets for the rails are roughly aligned vertically when the brackets are secured to the wall. To effect this alignment, a plumb line is extended down the hatchway in a certain position with respect to the ultimate position of the rails and the brackets are vertically aligned within certain limits by measurement from this plumb line, using brackets of different height and shims 17 to obtain the desired positions. A gauge is utilized in positioning the bracket faces at right angles to the intended plane of the rails and in setting the faces of opposite brackets parallel.

In accordance with the arrangement illustrated, the guide rails are secured to the brackets by clips 20 and bolts 21. These bolts extend through holes 22 in the clips and holes 23 in the brackets. The holes in the brackets are spaced apart a distance to provide a certain amount of clearance between the bolts and the rails. Inasmuch as the holes 13 and therefore the vertical centerlines of the brackets are only roughly aligned vertically, it is preferred to provide several pairs of holes 23 in the brackets for receiving the bolts 21. Such arrangement is illustrated in Figure 5. The holes of each pair are the same distance apart. A plumb line is also utilized for setting the guide rails. The faces of the rails are lined up by measuring in from the plumb line and adjusting their positions by means of shims 18 between the face of the brackets and the clips and backs of the rails.

To facilitate lining up the sides of the rails, a pair of wedges 24 is provided at each bracket, these wedges being in the spaces between bolts 21 and the edges 25 of the base of the rail. Each

clip is cut away at 26 to a point to permit the wedge to engage the bolts. Each wedge is provided with a foot portion 27 to retain the wedge in the opening between the bolt and the rail when the wedge is tapped upwardly. Also a vertical portion 28 is provided between the foot and the incline of each wedge to take care of the space from the bolt 21 and the bottom of the clip. To line up the sides of the rail, the clip bolts 21 are inserted in the pair of holes 23 of the bracket 10 which most nearly approximate the center as indicated by the plumb line. With the clips lightly tightened, the wedges are tapped to shift the rail to one side or the other until the sides of the rail are in proper position with respect to the 15 plumb line. The clips are then tightened down to hold the rail in adjusted position. In Figure 2 is shown an alignment obtained by forcing the rail well to the right while in Figure 3 is shown an alignment obtained by forcing the rail well to 20 the left. In case the rail alignment can not be obtained by forcing the rail to an extreme position, the clips are secured in the next set of holes 25 in the direction in which the rail is to be shifted. In this connection the distance between the centerlines between adjacent pairs of holes should be slightly less than the maximum shift obtainable with the wedges to insure proper adjustment. The angle of the wedges is such as to obviate the 30 wedges being forced upwardly by sidewise pressure.

The wedges not only provide a simple means for setting the rails but also provide a solid connection of the rails to the brackets. They also act to keep the rails in alignment should there be any tendency for them to shift. Thus, for example, should one of the bolts 21 become loose, the wedge for that side of the rail automatically holds the rail in proper position. The same is 35 true if both bolts become loosened. The wedges 40

are effective regardless of whether the bolts 12 are horizontally aligned or not as the wedges bear against the bolts 21. It is seen therefore that a very simple and reliable arrangement is provided for aligning the sides of the guide rails which acts automatically to retain the sides of the rails in alignment.

While the invention has been described in connection with the guide rail for an elevator car, it is also applicable to guide rails for counterweights. Also, it is to be understood that the invention may be utilized with various types of rail brackets and with various arrangements for securing the brackets. Also, the construction of the rail clips is only illustrative. As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

A fastening device for an elevator guide rail comprising, a bracket mounted in the hatchway, a pair of clips oppositely disposed, one on each side of the rail and positioned on a line perpendicular to the longitudinal axis of the rail, a bolt for each clip for securing the clip to the bracket, each clip being cut back to expose the bolt, and a wedge on each side of the rail underneath the clip between and engaging the edge of the base of the rail and the bolt, said wedges being oppositely movable vertically to shift the rail sidewise to align the sides of the rail and the bolts being tightened when the rail alignment has been effected to secure the rail to the bracket.

SELDEN BRADLEY SANFORD.
